GAME BOARD

Wilbert W. Costenbader, Wyomissing, Pa.

Application May 26, 1952, Serial No. 19,903

Term of patent 14 years

(Cl. D34—5)

To all whom it may concern:

Be it known that Wilbert W. Costenbader, a citizen of the United States of America, residing at Wyomissing, in the county of Berks and Commonwealth of Pennsylvania, has invented a new, original, and ornamental Design for Game Board, of which the following is a specification, reference being had to the accompanying drawing, forming part thereof wherein:

The single figure is a plan view of a game board embodying my new design.

The essential features of my design are shown in full lines. The game board shown is of conventional thickness.

I claim:

The ornamental design for a game board, substantially as shown and described.

WILBERT W. COSTENBADER.
